INVENTOR

John D. Karle
BY
Henry J. Miller
ATTORNEY

UNITED STATES PATENT OFFICE.

JOHN D. KARLE, OF ROSELLE PARK, NEW JERSEY, ASSIGNOR TO THE SINGER MANUFACTURING COMPANY, A CORPORATION OF NEW JERSEY.

LATCH.

Application filed May 3, 1919. Serial No. 294,414.

To all whom it may concern:

Be it known that I, JOHN D. KARLE, a citizen of the United States, residing at Roselle Park, in the county of Union and State of New Jersey, have invented certain new and useful Improvements in Latches, of which the following is a specification, reference being had therein to the accompanying drawings.

10 This invention relates to a latching device for separably securing two parts of a container such as a portable casing for sewing machines and the like.

15 It aims to provide a new and improved construction which is easily operated and which affords a secure fastening. It also comprehends an arrangement of the latching device which while readily accessible is reasonably secure against accidental release.

20 The construction comprises essentially a pair of pivoted levers having reversely arranged hooks on one pair of their adjacent ends and either finger-pieces or key fitting 25 openings on their opposite ends to which access for manipulation is provided by a countersunk opening in one of the two separable parts of the container on which the levers and a keeper-plate are respectively 30 mounted.

Other objects of the invention will appear in the following detailed description of the accompanying drawings, in which Fig. 1 represents one form of the invention in perspective. Fig. 2 represents a cross-section on line *a*—*b*, Fig. 1, looking in the direction indicated by the arrows. Figs. 3 and 4 represent in plan view a modified construction for the manipulating ends of the 40 lever in non-registering and registering position, respectively. Fig. 5 represents a cross-section on the lines *c*—*d*, Fig. 3, looking in the direction indicated by the arrows. Fig. 6 represents the form of key that may 45 be employed to operate the manipulating ends of the levers in their form illustrated in Figs. 3, 4 and 5. Fig. 7 represents in perspective the countersunk opening which may be provided in one part of the container 50 for access to the manipulating ends of the levers.

In the preferred form of the invention illustrated in Figs. 1 and 2, a base-plate comprising a body portion 1 and a flange 2 disposed preferably at right angles to the body

portion has pivoted to a raised portion 3 integral with the body portion 1 a pair of levers 4 and 5 preferably of the form and shape illustrated in the drawings. The levers 4 and 5 are preferably fulcrumed on the headed pins 6 and 7 which are riveted to the raised portion 3. The lower adjacent ends of the levers 4 and 5 are shaped to form hooks 8 and 9, respectively, which are normally urged apart by a spring 10 whose ends are coiled about fingers 11 and 12, formed on the outside edges of the levers 4 and 5, respectively, preferably between their fulcrums and hook ends. Through a slot 13 in the flange 2 the levers project in overlapping relation and their hooks 8 and 9 are adapted to enter a correspondingly shaped slot 14 in a keeper-plate 15 which is also provided with a hole 16 for a dowel pin 17 projecting from the lower face of the flange 75 2. Screws 18, 19 and 20 may be employed to secure the base and keeper-plates to the two parts of the separable container indicated by the numerals 21 and 22.

It will be noted from an inspection of Fig. 1 that when the hooks 8 and 9 are in retaining engagement with the keeper 15 they are spaced apart substantially the same distance as are the pivots 6 and 7. By this arrangement when force is applied to one of the two parts 21 or 22 of the container tending to separate them the pull on the hooks is substantially in parallel lines passing through the two spaced pivots 6 and 7. Thus it will be seen that there is practically no 90 tendency for the hooks to slide away from the keeper under this force and the liability of their being accidentally released is removed. Because of this action the spring 10 may be a very light one thus facilitating 95 the manual operation of the hooks when it is desirable to release them.

It is preferred to form the upper free ends of the levers 4 and 5 with manipulating finger-pieces 23 and 24, respectively, which are 100 bent at an angle to the body portion of the levers and are adapted to be projected through a counter sunk opening 25 provided in one part, 22, of the separable container. These finger-pieces may be pinched together 105 against the action of the thrust-spring 10 to approach the hooks 8 and 9 and bring them more nearly, if not exactly, into registration in order to permit of their withdrawal through the slot 14 in the keeper-plate 15. 110

Instead, however, of shaping the levers with finger-pieces 23 and 24, it may be preferred for some purposes to fashion the manipulatable ends of the levers with openings 26 and 27 which are adapted normally to occupy the relative positions illustrated in Fig. 3 under the action of the spring 10 when the hooks 8 and 9 are in the position illustrated in Fig. 1. With such a construction a key 28 having a rectangular shaped end 29 may be employed to enter the rectangular space indicated by the numeral 30, Fig. 3 and defined by the opposite side walls of the openings 26 and 27, to turn the levers until the openings register as indicated in Fig. 4. When the key 28 is employed to manipulate the upper ends of the levers it would be desirable to strike up a boss or raised portion 31 from the body of the base-plate 1 as indicated in Fig. 5 and to provide a circular opening 32 therein to receive and guide the reduced extremity 29 of the key, thus insuring equal and opposite displacement of the manipulatable ends of the levers.

Having thus set forth the nature of the invention, what I claim herein is:—

1. In a latching mechanism for detachably connecting two relatively movable parts of a container, in combination, a supporting plate, a pair of spaced pivots on said plate, levers mounted on said pivots and provided with opposed hooks, said levers comprising plates which overlap each other substantially throughout their lengths, a keeper plate adapted to cooperate with the hooks, yielding means urging the hooks into engagement with the keeper-plate, and manipulating means on each of the levers.
2. In a latching mechanism for detachably connecting two relatively movable parts of a cabinet, in combination, a support, a pair of spaced pivots on said support, levers mounted on said pivots and provided with

opposed hooks, said levers comprising plates 45 which overlap each other substantially throughout their lengths, a keeper plate adapted to cooperate with the hooks, yielding means urging the hooks into engagement with the keeper-plate, said hooks and keeper 50 plate so constructed and arranged that when the hooks are engaged with the keeper-plate they are separated a distance substantially equal to the distance between the pivots, and manipulating means on each of the levers. 55

3. In a latching mechanism for detachably connecting two relatively movable parts of a container, in combination, a support, a pair of levers pivoted to said support and provided with oppositely directed retaining 60 means, a keeper adapted to cooperate with the retaining means, yielding means connected to swing said levers about their pivots to urge the retaining means into engagement with the keeper, manipulating means on the 65 levers for swinging them in opposition to the yielding means, said support and levers adapted to be enclosed within a wall of the container and said wall being provided with an opening through which the manipulating 70 means are accessible.

4. In a latching mechanism, a support, a pair of levers pivoted to said support and provided with oppositely and outwardly directed hooks, a keeper in the form of a 75 slotted plate adapted to cooperate with said hooks, each of said levers provided with a finger bent up from the edge thereof, a spring supported by said fingers and adapted to urge the hooks into engagement with 80 the keeper, and said levers being provided with means whereby they may be manipulated and the hooks disengaged from the keeper.

In testimony whereof, I have signed my 85 name to this specification.

JOHN D. KARLE.
